(57) **CLAIM**

The ornamental design for a hand-held virtual reality headset, as shown and described.

DESCRIPTION

FIG. 1 is a front view of a hand-held virtual reality headset showing our new design;

FIG. 2 is a rear view thereof;

FIG. 3 is a plan view thereof;

FIG. 4 is a bottom view thereof;

FIG. 5 is a left side view thereof;

FIG. 6 is a right side view thereof;

FIG. 7 is a perspective view showing an upper front and left side thereof;

FIG. 8 is a perspective view showing an upper front and right side thereof; and,

FIG. 9 is a perspective view showing an upper rear and left side thereof.

1 Claim, 8 Drawing Sheets

FIG. 1

FIG. 2

FIG. 3

FIG. 4

FIG. 6

FIG. 5

FIG. 7

FIG. 8

FIG. 9
